UNITED STATES PATENT OFFICE.

KATHERINE F. CONLEY, OF CANTON, OHIO.

ATTACHMENT FOR HIGH CHAIRS.

1,050,205.

Specification of Letters Patent. Patented Jan. 14, 1913.

Application filed February 20, 1912. Serial No. 678,946.

To all whom it may concern:

Be it known that I, KATHERINE F. CONLEY, a citizen of the United States, residing at Canton, in the county of Stark and State 5 of Ohio, have invented a new and useful Improvement in Attachments for High Chairs, of which the following is a specification.

My invention relates to improvements for 10 attachment for high chairs adapted to be temporarily attached to a high chair.

The objects of my invention are, first, to provide a receptacle located in front and at the sides of the chair, said receptacle 15 designed to receive and hold various articles, and second, to provide means whereby the attachment can be easily connected to a chair and removed when not in use. These objects, together with other objects, readily 20 apparent to those skilled in the art, I attain by the construction illustrated in the accompanying drawings, although my invention may be embodied in other mechanical forms, the construction illustrated being 25 chosen by way of example.

In the accompanying drawing: Figure 1 is a perspective view of a high chair showing the attachment properly connected with parts broken away. Fig. 2 is a view showing a portion of one of the outer bars of the 30 chair back and illustrating one of the members of the receptacle frame properly connected. Fig. 3 is a top view of a portion of the receptacle frame and a transverse section of one of the bars of the chair back. Fig. 4 is a transverse section of the lap-board of a chair showing a front view of the 35 receptacle frame. Fig. 5 is a top view of the receptacle.

Similar numerals of reference indicate 40 corresponding parts in all the figures of the drawing.

In the accompanying drawing, 1 represents a chair which is of the usual construction 45 and within itself forms no particular part of the present invention. The chair is preferably provided with the ordinary lap-board 2, which is connected to the chair arms 3 in the usual manner. The receptacle 50 frame is made up of light bars of metal and consists of the chair connecting portions 4 from the outer ends of which the outer receptacle attaching member 5 is extended upward and around in front of the chair proper. The inner receptacle attaching 55 member 6 is connected to the chair attach-

ing members 4 and extended forward and spaced a suitable distance away from the outer member 5 for the purpose of so spacing the members that a flexible receptacle 60 can be attached.

For the purpose of supporting the front or forward portion of the receptacle frame proper, the brackets 7 are provided, which brackets are attached to the inner and outer 65 members of the receptacle frame and to which brackets is attached the cross or supporting bar 8, which supporting bar is designed to rest upon the chair seat as best 70 illustrated in Fig. 4.

For the purpose of connecting the rear portion of the receptacle frame the back of the chair is provided with the screws 9 or their equivalents, to which screw members 4 of the frame are connected slots 10, one end 75 of each of the slots being provided with an aperture 11 of sufficient size to allow the head of the screws 9 to pass, after which the members 4 are moved endwise so as to bring the slots 10 under the heads of the screws 9, 80 said frame being formed of spring material for the purpose of allowing the members 4 to be moved toward each other to be connected to the chair and then to move outward by the springing action of the members to which the receptacle 12 is attached. The receptacle 12 is formed of flexible material such as cloth of any desired kind and is connected in any convenient and well 85 known manner, but the receptacle 12 should 90 be so attached that it can be removed for the purpose of washing and for the purpose of providing for thus removing the receptacle the parts of the frame should be so joined together that they can be easily 95 detached preferably by clamping bolts 13.

It will be understood that by providing the frame and connecting the receptacle 12 as illustrated, said receptacle will be in position to catch any crumbs or food accidentally 100 dropped by a child and at the same time several toys may be placed in the receptacle and of easy access to the child.

Having fully described my invention what I claim as new and desire to secure by Letters Patent, is—

1. In an attachment for chairs, the combination of a chair, a receptacle holding frame consisting of inner and outer members, brackets connected to said inner and outer members and a supporting bar secured to the inner member of the receptacle sup-

porting frame and adapted to rest upon a chair seat and means for connecting the rear receptacle frame to a chair, and a receptacle carried by said frame, substantially as and 5 for the purpose specified.

2. In an attachment for chairs, the combination of a chair, a receptacle holding frame consisting of inner and outer members, brackets connected to said inner and 10 outer members and a supporting bar secured to the inner member of the receptacle supporting frame and adapted to rest upon a chair seat and means for connecting the rear receptacle frame to a chair, and a receptacle 15 detachably connected to the frame, substantially as and for the purpose specified.

3. In an attachment for chairs, the com-

bination of a receptacle or frame consisting of inner and outer members consisting of 20 spring material, the rear part of said frame adapted to be connected to the back of a chair, a supporting bar connected to the front or forward portion of said receptacle frame, said supporting bar adapted to rest 25 upon the seat of a chair and a receptacle carried by the frame, substantially as and for the purpose specified.

In testimony that I claim the above, I have hereunto subscribed my name in the 30 presence of two witnesses.

KATHERINE F. CONLEY.
